UNITED STATES PATENT OFFICE.

ROY A. RANGER, OF CHARLEVOIX, MICHIGAN.

LOG GRAPPLE.

Application filed June 9, 1922, Serial No. 567,211. Renewed December 27, 1924.

To all whom it may concern:

Be it known that I, ROY A. RANGER, a citizen of the United States, residing at Charlevoix, county of Charlevoix, State of Michigan, have invented a certain new and useful Improvement in Log Grapples, and declare the following to be a full, clear, and exact description of the same, such as will enable others skilled in the art to which it pertains to make and use the same, reference being had to the accompanying drawings, which form a part of this specification.

This invention relates to apparatus for salvaging sunken logs, and has for its object an improved arrangement of parts whereby the logs may be easily sought out by the points of the grapping hooks, as they lie more or less irregularly on the bottom of a lake or river, often partly buried in sand or mud, and whereby when grappled they may be most easily dislodged and raised. My improved device has particular reference to uniformity of action of the grapping members, regardless of the character of the bottom, whether hard, soft sand, mud, or weedy.

In the drawings:

Figure 1 is an elevational view of a grapple being towed from a scow, with one of its pronged arms just engaging a log partly buried in sand,

Figure 2 is a similar view, on a somewhat larger scale, showing both arms of the grapple engaging the log, which is being started from its buried position in the sand,

Figure 3 is a perspective of my improved grapple.

Figure 4 is a detail sectional view, taken along the line 4—4 of Fig. 1.

Figure 5 is a similar detail, taken along the line 5—5 of Figure 1.

Except in relatively shallow and very clear water, grapping for sunken logs is a more or less blind groping for the logs, whose presence in a given locality is generally known, because of the knowledge that lumbering operations have in former years been in progress along that particular stream or lake. But the exact positioning of the individual logs, whether each lies loosely on the stream or lake bottom, and the size of each, is a matter of surmise until each is raised to the surface after being grappled. Furthermore, a section of bottom which is relatively clear and hard and free of weeds may, and frequently does, adjoin a soft and

muddy portion, in which ordinary grapping tongs would sink so deeply as to be of little or no use for their intended purpose, even though operating well on another kind of bottom. And provision must be made, as to the operation of the parts of the grapple relatively to one another, so that a log, when grappled, may be firmly seized and held, whatever its size be, while it is being raised to the surface.

To this end, I have devised the apparatus herein disclosed and claimed, which is peculiarly adapted to accommodate itself to the irregularities in the character and contour of the bottom over which it is being towed, and which, when a log has been encountered, can be relied upon to hold it against slippage. It consists of a pair of tongs A and B pivotally joined near their centers, as at C, each being provided at its lower end with an in-turned point or hook designed to sink into the wood when the log is grappled. With the upper end of the arm A is loosely connected, as by the link or swivel D, the lazy tongs link E, while to the upper end of the arm B is similarly connected the lower end of the link F. The upper end of the link E is pivotally connected with the center portion of the link F by pivot G, and the upper end of the link E has attached to it the cable H, by which the grapple is suspended from the scow J. To the lower end of the arm B is attached the lower end of the rope or cable K, by which the arm B is held in raised or non-grappling position as the device is being drawn along the lake or river bottom.

The grapping arm portion of the device thus far described would, of course, sink to the bottom, and, in the case of a mud bottom, sink thereinto, and in the case of a hard bottom would fall over on its side in such a position as to be of little or no use, were it not for the connection with it of the float member L, preferably constructed of watertight pipe, or filled with a buoyant packing, which is rather loosely pivoted at its slightly opened forward end, as at V, to the upper end of the arm A, with its bowed or circular portion lying generally above the rearward or lower end of the arm A, with which the center of the curved portion is loosely connected by the chain M. This member L is so designed as to its shape and its buoyancy relatively to the hooks or grapping arms, that, as the device is towed along the

bottom, it assumed a position midway between such a degree of buoyancy that it would float on the surface and such an absence thereof, that it would sink to the bottom. And since the loose pivot and the link connections between the float and the grapping hooks are situated on the former at substantially opposite points in its curved outline, when viewed from above or beneath, the log-grappling members are suspended substantially beneath this semi-buoyant ring, thus sustaining the hooks near the bottom, so that while the rearward arm A can seize with its point the imbedded or partly embedded log, it still keeps the grapple from sinking too far relatively to the bottom so that its weight, when it strikes a stone or similar obstruction, would make it jump completely over an adjacent log, or fall over onto one side in such position; and yet the loose character of the support afforded by the chain M insures the positioning of the hooks because of their own weight in most effective operating position relatively to the bottom that is being dragged, and the looseness of the float member's connection with this chain connection and its pivoting enables it to rock or sway from one side to another as regards horizontal positioning, according to the incline of the bottom being traversed or to obstructions which it encounters, without effecting any substantial change in the desired upright positioning of the log-grappling hooks.

In operation, as soon as a log has been caught by the point of the arm A, which can be sensed by the increased pull upon the cable H, the operator in charge of the rope K lowers the same, so that the arm B can respond to the increased pull on the cable H, due to the lazy-tongs action of the links E and F, and when the log has thus been firmly gripped by both hooks, it can be drawn to the surface; extra hook points, as N, may, if desired, be added to the inner or log-engaging surface of one of the arms as A. It should be observed that by the arrangement of the arms I have shown, a log, which when grappled, may be pried or drawn away from its more or less embedded position in the sand by what may be described as a rolling or canthook action. This, with a minimum of effort, permits a strong leverage of a twisting character to be applied for overcoming the suctional resistance to its dislodgment.

What I claim is:

1. In a grapple, in combination with an annular float and protective member adapted to maintain a substantially horizontal position, a pair of pivotally associated grapple arms adapted to be held by manual pull upon a connected rope member in open posi-

tion and in a substantially vertical plane beneath said annular float member, lazy tong members for drawing said grapple arms together contemporaneously with the cessation of manual pull upon said rope, and loose connecting means between said grapple arms and said annular float member, whereby the irregular upward and downward movement of said grapple arms due to their striking against unexpected obstructions is communicated in only slight degree to said annular float member.

2. In combination with a pair of pivotally united and normally opened grapple arms, link members at their upper ends for drawing the arms into engaging position about a log, and a circular horizontally disposed float member having a loose connection with said grapple arms, the vertical plane of which extends substantially centrally thereof, whereby they are semi-buoyantly sustained in position for limited vertical movement independently of the float according to the objects encountered.

3. A grapple, having in combination with a relatively buoyant annular float member, a pair of normally open grapple arms supported from oppositely disposed portions of the periphery of said float member in a substantially vertical plane, the connection between said parts being flexible, thereby minimizing the obstacle-induced movements of said grapple arms communicated to said float member, and manually controlled means for regulating the drawing together of said grapple arms.

4. In combination with a horizontally positioned relatively buoyant ring, a pair of pivotally related grapping members loosely suspended from oppositely disposed points on said ring in a way to transmit to said ring in a modified degree only the irregular movements of said grapping members, and supporting and hoisting ropes operatively connected with said grapping members.

5. The combination, with a pair of pivotally connected grapping arms, of a relatively buoyant annular member, and means flexibly connecting said grapping arms with peripherally opposite portions thereof, whereby the grapping arms are loosely supported in a substantially vertical plane, regardless of the temporary displacement of either member from its intended position, due to striking of external obstacles.

In testimony whereof, I sign this specification in the presence of two witnesses.

ROY A. RANGER.
